CONVEYER SYSTEM FOR ASSEMBLY LINES
AND THE LIKE

Isadore Galper, Manchester, N. H.

Application December 30, 1950; Serial No. 203,724

7 Claims. (Cl. 193—19)

1

This invention relates to improvements in conveying apparatus. More particularly it provides a new and improved conveyor system which includes a continuous circuitous conveyor, or any desired number of continuous circuitous conveyors, on which any of numerous things may be circulated past stations distributed along the conveyor system thereby to provide one or more pools of whatever is being conveyed, from which pool or pools the stations may be supplied, with whatever is being conveyed, on principles of automatic ejection, selection and rejection, depending upon the requirements at particular stations.

The invention has general utility in the conveying field and will be found especially advantageous for conveying work units or parts, or anything else that may be desired, to the various stations along an assembly line, or the like. It is herein disclosed in connection with an assembly line along which workers at the various stations perform particular operations or duties incident to the assembly of work parts which deliver to the work stations in partitioned boxes. It should be understood, however, that the work parts, or whatever is being conveyed, may be variously delivered at the stations to suit any particular requirements, the boxes of work parts herein shown being exemplary rather than limiting in this respect.

Prior conveyor systems of types suitable for assembly lines, and the like, so far as I am aware, have operated on principles of predetermined timing and critical balancing of the operations to be performed at all of the stations along the assembly line. Heretofore, any predetermined timing and critical balancing of such conveyor systems has been greatly influenced by the slowest worker or workers along the line. One abnormally slow worker might be the means of delaying the workers at all subsequent stations waiting for the output of the abnormally slow worker. Hence, it has not been practicable with the prior assembly line conveyor systems to employ piece-work incentives, or to speed up the assembly operations beyond the capabilities of the slower workers along the line.

It is among the objects of my present invention to provide a conveyor system, suitable for assembly lines, and the like, which operates on principles which make it unnecessary to predetermine and establish any critical balance in the timing of work operations at successive stations along an assembly line. According to the invention, workers at the various stations receive work from continuous circulating pools of work,

and the individual workers along a pool receive work automatically from the pool only as fast as each can handle it, with the output of all of the workers along the pool delivering to a station further along the line or to one or more other pools further along the line.

Another object is to provide a conveyor system suitable for assembly lines, and the like, wherein the work circulates in continuous circuitous pools at successive locations along the system and automatically delivers to stations distributed along the pools only as fast as the individual workers at the stations can handle it, whereby it becomes feasible to employ piece-work incentives for increasing the output of the individual workers. By thus maintaining a circulating supply of work from which individual workers are supplied automatically in accordance with their individual outputs, and advancing the cumulative output of workers at any particular pool to stations or pools further along the line, each individual worker may work as fast or as slow as he or she desires or is capable of, and the fact that one worker may work fast and another slow will be averaged in the cumulative output of all of the workers at any particular pool.

Still another object of the invention is to provide a method for delivering work to work stations along an assembly line, or the like, whereby a plurality or a series of continuous circuitous pools of work are arranged and adapted to deliver work selectively to work stations distributed along the respective circuitous pools, and the supply of units of work in successive pools along the assembly line is maintained by deposit therein of units of work coming from work stations distributed along one or more preceding pools of work.

A further object of the invention is to provide a conveying apparatus wherein a centrally disposed conveyor may extend from one end to the other of an assembly line, or the like, or along a portion thereof, and any suitable number of continuous circuitous conveyors are arranged in succession along the centrally disposed conveyor with any suitable number of stations distributed along the circuitous conveyors, one or more of the circuitous conveyors being supplied from the centrally disposed conveyor with whatever is being conveyed, and each of the circuitous conveyors providing a pool from which a unit of whatever is being conveyed delivers selectively to any particular station only after a previously delivered unit at that station has been removed from the location to which it had been delivered.

2

Yet another object of the invention is to provide conveying and delivering apparatus wherein a succession of circuitous conveyors provide pools of whatever is being conveyed, and units of whatever is being conveyed deliver from the pools to stations distributed along the circuitous conveyors, and a centrally disposed conveyor replenishes the supplies of units in at least some of the pools, there being automatically responsive means at stations along each circuitous conveyor whereby a unit delivers from a said pool to any particular station only after a previously delivered unit has been removed from the receiving position at that station, and there being deflector means for directing units from the centrally disposed conveyor to at least one of said stations, and automatically responsive means for delivering units from the centrally disposed conveyor to one or more of the circuitous conveyors.

A still further object of the invention is to provide conveying and delivering apparatus wherein three belt conveyors extend in parallelism along an assembly line with the central conveyor elevated above the other two and with said other two travelling in opposite directions, there being rotatable elements at spaced locations along the conveyors arranged and adapted to carry units of whatever is being conveyed from one to another of the two oppositely travelling lower conveyors, whereby said units on the lower conveyors travel in circuitous paths between the rotating elements to provide pools of said units from which individual units may deliver to stations along the circuitous paths in response to removal of a previously delivered unit from the receiving position of any particular station.

It is, moreover, my purpose and object generally to improve conveying systems and more especially such systems which are suitable for supplying conveyed items selectively to the stations along an assembly line, or the like.

Fig. 18 is a side elevation of the portion of the apparatus shown in Fig. 17; and

Fig. 19 is a wiring diagram showing one way of effecting electrical connections and circuits for operating the illustrated conveyor system.

Referring to the drawings, the apparatus represented in Fig. 1 provides an assembly line of generally U-shape having work stations distributed along only the generally parallel legs A and B of the U. This illustrated apparatus, for illustrative and descriptive purposes, includes six circuitous conveyor pools distributed along the parallel legs A and B but it should be understood that the invention may be embodied in apparatus having but a single circuitous pool or any other desired number of the pools.

In Fig. 1, a work table 10 extends along the leg A, providing oppositely disposed work stations distributed along the opposite sides of the table. In a similar manner, a work table 12 extends along the leg B, providing oppositely disposed work stations distributed along the opposite sides of table 12.

According to the invention, units of work progress from station 1 or 1a, at the left hand end of table 10 in Fig. 1, to the opposite end of table 10 through the medium of three conveyor belts 14, 16, 18 which are centrally disposed in parallelism between the opposite sides of the table and above the plane of the top of the table. The middle conveyor belt 16 is elevated somewhat above the level of the belts 14, 18 (Figs. 3 and 4) and constitutes a main conveyor from which units of whatever is being conveyed may be transferred directly to particular stations and to particular circuitous pools as later described herein in greater detail.

Workers at various stations along the table 10, after completing operations on units delivered to those stations, place the units on central conveyor belt 16 for delivery to stations further along the assembly line.

When units of work are being conveyed along the assembly line, the units on central conveyor belt 16 at the right hand end of table 10 in Fig. 1 are delivered to the right-angularly related conveyor belt 20 which in turn delivers them to the central elevated conveyor belt 22 which, with conveyor belts 24, 26, is centrally disposed between the opposite sides of the table 12 and above the plane of the top of table 12. Work units delivered to conveyor belt 22 progress to the left along table 12 and will be removed from the assembly line at station 31 or 31a at the left hand end of the table 12, either manually or otherwise.

The particular U-shaped assembly line illustrated in Fig. 1 is designed to provide an adequate length of assembly line within a building

which could not accommodate a straight assembly line of the same length. It should be understood, however, that the features of the invention may be employed in straight assembly lines, U-shaped assembly lines, and in assembly lines which may extend sinuously back and forth across the length or width of a room as many times as may be required to attain a needed over-all length of assembly line. Also, it should be understood that the number of work stations as represented in Fig. 1 is exemplary and was selected for convenience of illustration. Actually, the assembly line apparatus may be made up of sections adapted to be assembled together to provide an assembly line of any desired length and having any desired number of stations and circuitous conveyor pools.

Considering first the progress of work units along the table 10, the conveyor belts 14, 16, 18 extend over suitable pulleys at the opposite ends of the table, the pulleys at the left hand end of table 10 in Fig. 1 being mounted within the housing 11, and the pulleys at the right hand end of table 10 in Fig. 1 being mounted within the housing 11'. As best seen in Figs. 6-9, the housing 11' at the right hand end of table 10 houses an electric motor 28 which supplies the power for driving the conveyor belts 14, 16, 18, the upper run of the belts 14, 16 being driven to the right in the direction of advance of work along table 10, while belt 18 is driven in the opposite direction. Any suitable drive connections may be employed between motor 28 and the main conveyor pulleys in housing 11'. Figs. 7 and 9 show all three of the main pulleys 30, 32, 34 mounted on shaft 36. Pulleys 30 and 32 are fixed on shaft 36 for rotation in unison, while pulley 34 is loose on the shaft. The motor 28, through reduction gearing within casing 38, drives shaft 40 counter-clockwise in Fig. 9, and shaft 40 has chain and sprocket connection for driving shaft 42 counter-clockwise. Shaft 42 has chain and sprocket connection to pulley 34 for driving it counter-clockwise in Figs. 7 and 9. Shaft 42 also has gear connection to shaft 44 for driving it clockwise at the same speed that shaft 42 is driven counter-clockwise. Shaft 44 has chain and sprocket connection to shaft 36 for driving pulleys 30 and 32 clockwise in Figs. 7 and 9.

The main conveyor pulleys 46, 48, 50 in housing 11 at the left hand end of table 10 all are mounted on shaft 52 (Figs. 6 and 8), and all may be loose on the shaft. Preferably the shaft will be adjustably mounted on its support, as at 54 in Fig. 8, to permit adjustment of the tension of conveyor belts 14, 16 and 18.

Throughout their extents along the table 10, the upper runs of the conveyor belts 14, 16, 18 are supported and guided in suitable tracks, such as the sheet metal tracks as represented at 15, 17 and 19 in Figs. 3 and 4.

Circuitous pools of work are provided at suitable locations along the table 10, and each pool may have extent past any desired number of work stations. In Fig. 1, the table 10 has three circuitous pools of work, one extending between the pair of rotatable disks 56, 58, another extending between the pair of rotatable disks 60, 62, and the third one extending between the pair of rotatable disks 64, 66. For convenience, the work stations extending along the opposite sides of each circuitous pool of work in Fig. 1 are numbered to indicate that four work stations are located along each side of each circuitous pool. It should be understood, however, that any desired number of pools may be provided, and that

the individual pools may be as long as desired, with as many work stations located along the respective pools as may be desired.

Referring more particularly to Figs. 2 and 3, the illustrated relation of the rotatable disk 56 to the conveyor belts 14, 16, 18, and the structure of disk 56, are representative of the relation and structure of the other similar disks 58, 60, 62, 64 and 66. Disk 56 is rotatably supported in a bearing piece 68 secured to the under sides of the belt tracks 15, 19, there being an opening 70 through table 10 for accommodating bearing piece 68 and the depending shaft 57 of the disk. Actually, however, the disk may rest by gravity on the two oppositely travelling conveyor belts 14, 18 so that the belts frictionally engage and tend to rotate the disk. In some cases, the friction between the disk and the travelling belts may be relied upon for rotating the disk. However, it will be found desirable in most cases to positively drive the disk, and a suitably small frictional horse power slow speed electric motor is represented at 59 in Fig. 3, suspended from bearing piece 68 and directly coupled to the disk shaft 57. This motor 59, and the similar motors for the other disks, may be connected for operation whenever the conveyor belts operate.

The two belt tracks 15 and 19 are herein shown as formed from a single piece of sheet metal, with a central raised platform part 17' extending between tracks 15, 19 and supporting the elevated central belt track 17, as best seen in Fig. 4. However, it usually will be found more convenient to form the tracks 15, 19 and platform part 17' in three separate pieces secured together by any conventional means. The hub part 57' of the disk fits under the platform part 17' with slight extent through openings in the opposite side walls which lead between the tracks 15, 19 and the platform 17'. A fixed curved guide rail 72 extends around a substantial portion of the periphery of disk 56 for guiding work boxes, or the like, as they are being carried on the disk from belt 18 to belt 14. The mentioned openings in the opposite side walls which extend between tracks 15, 19 and platform 17' are large enough to permit passage of the work boxes, or other units of work, from one to the other of the belts 14, 18. Also, the platform part 17' which supports the central belt track 17 must be elevated enough above the disks to permit the work boxes, or other units of work, to pass under platform part 17' when being carried on a disk from one to the other of the conveyor belts 14, 18.

Inasmuch as the structure and arrangement of disks 58, 60, 62, 64 and 66 are the same as has been described in connection with disk 56, no further detailed description of the disks is considered necessary.

Reverting to the showing of Fig. 1, work units which are to proceed along the table 10 may be stacked on the table at station 1 or 1a, and a worker places them in succession on the central conveyor belt 16. Inclined tracks 74, 74a lead from the central belt 16 respectively to the work stations 2 and 2a, and a deflector plate 76 is adjustably mounted at 77 and may be set for deflecting the work units on belts 16 to either one of the inclined tracks 74 or 74a. As represented, plate 76 is set to deflect the work units to inclined track 74 and the units deliver from the track to the table 10 at station 2. A worker at station 2 may inspect each unit of work and, if a unit meets with approval, it is placed on the lower conveyor belt 14 or, if the assembly line is just getting into

operation, some work units at station 2 may be placed on lower conveyor belt 14 for building up the circuitous pool of work between the disks 56, 58 while others may be placed on the central conveyor belt 16 for delivery to a station further along the table 10.

Obviously, if desired, the operation of placing the work units on the central belt 16 at station 1, and the deflecting of the units to station 2, may be eliminated, and the worker at station 2 may take units directly from the supply at station 1.

According to the invention, work units placed on conveyor belt 14 by the worker at station 2 travel circuitously past stations 2, 3, 4, 5, 5a, 4a, 3a, 2a until ejected from belt 14 at some one of these stations. The units travel to the right in Fig. 1 to the disk 58 which transfers them to belt 18 for travel to the left. When they reach disk 56, it transfers them back to belt 14.

A switch button 78 projects a little above the top of table 10 at a work-receiving location at each of the stations 3, 4, 5, 4a, 3a and 2a. Each of these buttons 78 is biased to closed position but is adapted to be depressed to open position by the weight of a work unit resting on a button at work-receiving location. Fig. 2 shows work units in the form of rectangular boxes W and W' resting on the buttons 78 at work stations 2a, 3 and 3a, and shows other boxes W and W' circulating between the disks 36, 38. Fig. 4 shows the box W depressing the button 78 to open position at station 3, while the button 78 for station 2a, at the other side of table 10, is shown in its elevated closed position, the box W' which is shown on this latter button in Fig. 2 being omitted in Fig. 4.

An ejector mechanism, indicated generally at 80, in Figs. 2 and 4, and shown in detail in Figs. 15 and 16, is mounted opposite each switch button 78. Each ejector mechanism 80 may comprise a sheet metal plate 82 shaped as in Fig. 4 for fitting within the space provided under the platform 17, between the conveyor belts 14, 18 and below the conveyor belt 16. A combined eccentric and cam 84 (Fig. 15) is rotatably mounted on the upper side of plate 82 and has pin-in-slot connection to one end of an actuating lever 86 which is pivoted at 88 on the plate. The other end of lever 86 has pin-in-slot connection to an ejector element 90 which is slidably mounted in guide 92 on plate 82. One end of ejector element 90 is equipped with the pusher foot 91 for engaging a work box W or W' when the ejector element 90 is operated toward its outermost position as shown in Figs. 2, 15 and 16.

The shaft 85 of the combined eccentric and cam 84 extends through plate 82 and is connected to a mechanism mounted at the under side of the plate and indicated generally at 94. Mechanism 94 may be a well known clockwork type mechanism which is adapted to rotate shaft 85 when its coil 95 is energized in response to closing of a switch button 78 provided that the ejector circuit is otherwise conditioned for an operation of the ejector. However, the ejector circuit will be so conditioned only if and when a work unit W or W' is in a position bridging a pair of spring contacts in series with the particular switch button 78 which has closed.

Figs. 2 and 15 show two pairs of spring contacts 96, 98 and 96', 98' mounted on a supporting projection 100 which extends outward over the conveyor belts 14, 18. There will be one of these projections 100 at the approach to each work station to which work is to be ejected from a circuitous pool. As best seen in Fig. 15, each pair

5 of spring contacts 96, 98 and 96', 98' is mounted on a separate block so that one, two or more of the separate blocks may be mounted on a projection 100 to provide as many pairs of contacts 96, 98 and 96', 98' as may be desired at the approach to any particular work station. Each work unit W has a metallic contact 102 thereon in position to bridge the pair of spring contacts 96, 98 on any one of the projections 100 as the work unit moves to a contact bridging position opposite one of the switch buttons 78. Similarly, each work unit W' has a metallic contact 102' thereon in position to bridge the pair of contacts 96', 98' on any one of the projections 100 as the work unit moves into a contact bridging position opposite one of the switch buttons 78. As best seen in the wiring diagram of Fig. 19, each pair of spring contacts 96, 98 and 96', 98' at the approach to any particular work station is in series with the switch button 78 at that station in an ejector circuit for that station. Hence, before an ejector mechanism 80 can operate to eject a work unit from a conveyor belt 14 or 18 to any particular work station, the switch button 78 at that station must be closed and also the spring contacts 96, 98 or 96', 98' at the approach to that station must be bridged by a work unit contact 102 or 102'. When both of these conditions prevail, a circuit is closed to energize the step-up transformer 104 and the relay 105 of the affected ejector mechanism 80. When the relay is energized, it closes the high side of the transformer through the motor which rotates the combined eccentric and cam 84. A holding switch 106 (Figs. 15 and 19) is closed by the cam as soon as the cam starts rotating thereby to maintain the transformer 104 energized until the cam makes a complete rotation, at which time the low portion of the cam permits the holding switch 106 to open. This single rotation of the combined eccentric and cam 84 will have effected a complete out and back cycle of movement of the ejector element 90, thereby to eject a work unit W or W' from a conveyor belt 14 or 18 to a work-receiving location at one of the work stations. The arrival of the ejected work unit at a particular work station depresses the switch button 78 at that station thereby opening the ejector circuit.

50 Hence, assuming that a worker at station 2 is placing an adequate number of work units W or W' on the lower conveyor belt 14, a circuitous pool of work between the disks 56, 58 will be available from which a unit of work will be ejected to any one of the stations 3, 4, 5, 4a, 3a, 55 2a as soon as a previously ejected unit of work has been removed from the work-receiving position at that station. If a worker at one of these stations is slower than the workers at the other stations, the latter workers receive work as fast as they can handle it, and the slower worker receives work only as fast as he or she can handle it.

60 When the assigned task has been performed on a work unit at one of the stations 3, 4, 5, 4a, 3a or 2a, the worker at that station places the unit on a central conveyor belt 16 from which it is delivered to station 6 by means of a deflector plate 76 and inclined track 78 similar to the plate 76 and track 74 which deliver work units to station 2. The worker at station 6 inspects the work units and, if they are found satisfactory, places them back on central conveyor belt 16 for delivery to station 7 by means of a deflector plate 75 76 and track 78 as described in connection with

the delivery of units to station 2. If desired, the deflector plates 76 controlling delivery to stations 6 and 7 may be set to deflect the units to tracks 74a, for delivery to stations 6a and 7a instead of to stations 6 and 7.

The worker at station 7 places the units on the lower conveyor belt 14 to start or replenish the circuitous pool of work between the rotating disks 60, 62. Each of stations 8, 9, 10, 9a, 8a and 7a along this second pool has a switch button 78 and ejector mechanism 80 associated therewith for supplying work to these stations as fast or as slow as individual workers can handle it, in the same manner described in connection with stations along the circuitous pool of work between the rotating disks 56, 58.

Workers at stations along the second circuitous pool having completed their assigned task on work units W or W' place the units on the central conveyor belt 16 which carries them to the right, in Fig. 1, until the leading work unit on belt 16 is stopped opposite stations 11 and 11a by a fixed transverse abutment 108 which has a switch contact 110 thereon adapted to be held closed when a work unit is stopped against abutment 108. Switch contact 110 is in a circuit to a transfer mechanism indicated generally at 112, which is adapted to transfer work units from the central belt 16 to the lower conveyor belt 18 thereby to automatically maintain the supply of work units in the third circuitous pool of work which operates between the rotating disks 64, 66, at the right hand end portion of table 10. Each of stations 12, 13, 14, 13a and 12a along this third circuitous pool has a switch button 78 and an ejector mechanism 80 associated therewith for supplying work to these stations as fast or as slow as the individual workers can handle it, in the same manner described in connection with the stations along the first circuitous pool operating between the rotating disks 56, 58. The workers along this third pool, having completed their assigned tasks on work units, place the units on central conveyor belt 16 for delivery to the transverse conveyor belt 20, which, in turn, delivers them to the central conveyor belt 22 which travels to the left along table 12.

Three circuitous pools of work are illustrated in Fig. 1, along the table 12 of leg B of the disclosed assembly line apparatus, one pool extending between the rotatable disks 114, 116; another extending between the rotatable disks 118, 120; and the third one along table 12, extending between the rotatable disks 122, 124. It should be understood, however, that the assembly line preferably will be made up of separate sections which may be variously moved and combined to produce any desired number of work stations and any desired number of continuous circuitous pools, with suitable electrical plug-in electrical connections for the respective sections. For example, a section having rotatable disks may be substituted for a section not having disks, or vice versa, whereby the invention provides an extremely flexible assembly line which may be quickly adapted to any particular conditions or requirements.

In Fig. 1, the stations are numbered to indicate that there are six stations along each side of the circuitous pool which operates between disks 114, 116; five stations along each side of the circuitous pool which operates between disks 118, 120; and five stations along each side of the circuitous pool which operates between disks 122, 124.

124. These numbers may be varied as may be desired.

The conveyor belts 22, 24, 26 for table 12 may extend over pulleys at the opposite ends of the 5 table in the same manner as the conveyor belts 14, 16, 18 for table 10. However, as shown in Figs. 1, 11 and 12, the drive for belts 22, 24, 26 is at the left hand end of the table 12 where a housing 13 encloses motor 126 which drives the 10 two pulleys 128, 130 in unison counter-clockwise and drives pulley 132 clockwise, in generally the same manner that the pulleys 30, 32 and 34, at the right hand end of table 10, are driven.

Pulleys 134, 136, 138 at the right hand end of 15 table 12 may be loosely mounted on shaft 140 within the housing 13', with means 142 for adjusting shaft 140 to vary the tension on belts 22, 24, 26.

Figs. 7, 9, 11 and 12 show the transverse conveyor belt 20 extending over a pulley 144 in housing 11' and over a pulley 146 in housing 13', the pulley 144 having chain and sprocket drive connection to a shaft 148 in housing 11' which has gear connection to shaft 44. The transverse belt 25 20 extends under central conveyor belt 16 at table 10 and over central conveyor belt 22 at table 12, and there is guide means 150 for directing work units from the belt 16 to the belt 20 at table 10, and guide means 152 for directing work units 30 from belt 20 to belt 22 at table 12.

Work units delivering from belt 20 to belt 22 are carried to the left until a unit is stopped opposite stations 15, 15a by the fixed transverse abutment 154 which has the spring contact 110 35 thereon adapted to be held closed when a work unit is stopped against the abutment 154. Spring contact 110 is in a circuit to a transfer mechanism indicated generally at 112, which is adapted to transfer work units from the central belt 22 to the lower conveyor belt 26 thereby automatically to replenish and maintain the supply of work units in the circuitous pool which operates between the disks 114, 116. Each of stations 16, 17, 18, 19, 19a, 18a, 17a and 16a 40 along this circuitous pool has a switch button 78 and an ejector mechanism 80 associated therewith for supplying work from the pool to these stations as fast or as slow as the individual workers can handle it, in the same manner described in connection with the delivery of work from the pools along table 10, each worker, after completing the assigned task on a work unit, placing it on central conveyor belt 22 for advance to the left along table 12.

Work units moving to the left on conveyor 22 from the stations along the circuitous conveyor operating between disks 114, 116 are stopped by the fixed transverse abutment 156 with the leading work unit opposite work stations 21, 21a, 50 and the abutment has a spring contact 110 thereon adapted to be held closed when a work unit is stopped against the abutment 156. The spring contact 110 is in a circuit to a transfer mechanism indicated generally at 112, which is adapted to transfer work units from the central belt 22 to the lower conveyor belt 26 thereby to automatically replenish and maintain the supply of work units in the circuitous pool which operates between the disks 118, 120. Each of stations 21, 23, 24, 25, 22a, 23a, and 24a along this latter circuitous pool has a switch button 78 and ejector mechanism 80 associated therewith for supplying work from the pool to these stations in the same manner described in connection with 55 the circuitous pools along table 10, each worker,

60 65 70 75

11

after completing the assigned task on a work unit, placing the unit on central conveyor belt 22 for travel to the left toward the circuitous pool operating between the disks 122, 124.

Work units placed on central belt 22 at the stations 22, 23, 24, 25, 22a, 23a and 24a travel to the left until stopped by the fixed transverse abutment 158 with the leading work unit opposite work stations 26, 26a. Abutment 158 has a spring contact 110 thereon which is adapted to be held closed when a work unit is stopped against the abutment 158. Spring contact 110 is in a circuit to a transfer mechanism indicated generally at 112, which is adapted to transfer work units from the central conveyor belt 22 to the lower conveyor belt 26 thereby automatically to replenish and maintain the supply of work units in the circuitous pool of work units operating between the disks 122, 124. Each of the work stations 27, 28, 29, 30, 27a, 28a and 29a along this last one of the circuitous pools has a switch button 78 and an ejector mechanism 80 associated therewith for supplying work from the pool to these stations in the same manner described in connection with the pools of work along table 10, each worker, after completing the assigned task on a work unit, placing the unit on central conveyor belt 22 which carries it to the left hand end portion of table 12 where a worker at station 31 or 31a may remove the units. An abutment 160 at the extreme end of table 12 stops the units on belt 22 in positions for convenient removal.

All of the transfer mechanisms 112 for automatically maintaining the supply of work units in circuitous pools may be the same, and are shown as generally similar to the earlier described ejector mechanisms 80. However, the mechanism 112 for the circuitous pool at the right hand end portion of table 10 is arranged for transfer of work units from central belt 16 to the belt 18 which is travelling to the left along table 10, while each of the mechanisms 112 for the circuitous pools along the table 12 is arranged for transfer of work units from central belt 22 to the belt 26 which is travelling to the right along table 12.

As best seen in Fig. 17, each mechanism 112 has a pusher element 168 slidably mounted in the guide 170 which is fixed on the bottom 172 of an enclosure whose side and top walls are removed in Fig. 17. A platform 174 is suitably supported in spaced parallel relation to bottom 172 (Fig. 18), and this platform has a clockwork mechanism 176 mounted on its upper side whose coil 177, when energized, effects rotation of a shaft 178 which extends through platform 174 and has a combined eccentric and cam 180 fixed on its lower end at the under side of the platform. A step-up transformer 182 is controlled by relay 183 (Fig. 19) whose coil is in series with the low side of the transformer. When the relay is energized, the high side of the transformer becomes connected to the coil 177 so that the shaft 178 rotates whenever the relay 183 is energized. An actuating lever 184 is pivotally mounted at 186 on bottom 172 and has pin-in-slot connection at one end to the pusher element 168 and pin-in-slot connection at its other end to the combined eccentric and cam 180. Pusher element 168 has a pusher foot 169 thereon for broadly engaging a work box or other unit during a cycle of operation of the transfer mechanism. A single rotation of the combined eccentric and cam 180 effects a cycle of out and back

12

movement of pusher element 168 for lateral transfer of a work unit which may be stopped against one of the abutments 108, 154, 156 or 158.

Fig. 17 illustrates that transfer mechanism 112 which has abutment 154 associated with it, the spring contact 110 on the abutment being in the circuit to the relay 183 and open excepting when a work unit W or W' is stopped against abutment 154.

However, even though spring contact 110 in Fig. 17 may be closed, the circuit to transformer 182 will not be energized unless there is a vacant space on lower conveyor belt 26 opposite the pusher foot 169 for reception of a work unit. A suitable number of normally closed spring contacts 188 are distributed along the path of travel of conveyor belt 26 in position to be pressed inward to open position whenever a work unit on belt 26 is passing one of the spring contacts 188. Three such spring contacts 188 are illustrated in Figs. 17 and 18, spaced apart slightly less than the length of a work unit W or W'. Hence, unless belt 26 is free of any work unit throughout the extent of the distribution of the contacts 188, one or another of the contacts will be held open. The contacts 188 are in series with each other and with abutment contact 110 in the circuit to the relay 183.

Assuming that a work unit is stopped against abutment 154, holding its contact 110 closed, and assuming that all three of the spring contacts 188 in Fig. 17 are closed, indicating an adequate vacant space on belt 26 for reception of a work unit, the relay 183 will be energized and the high side of transformer 182 will be connected for a rotation of the combined eccentric and cam 186 thereby to move the pusher element 168 transversely of belt travel for pushing the work unit at abutment 154 off belt 22 and over belt 26, as represented in Fig. 17. The initial rotation of combined eccentric and cam 186 closes the holding switch 190, as best seen in Fig. 19, thereby to maintain the relay and transformer energized throughout a complete rotation of the cam even though one of the spring contacts 110, 188 may open during the cycle of operation of the transfer mechanism.

Inasmuch as central belt 22 is elevated above the plane of belt 26, a tiltable plate 192 is pivotally mounted at 194 in position to receive a work unit as it is pushed off the center belt 22. Plate 192 normally stands in a horizontal plane, elevated above belt 26 sufficiently to permit work units on the belt to pass under it without any interference. However, when a work unit is pushed onto plate 192 from center belt 22, the plate automatically tilts by gravity about its pivot thereby to bring an end portion of the work unit into engagement with the travelling belt 26 and the work unit is carried along on the belt, leaving the plate free to swing back to its horizontal position, ready to receive another unit.

Inasmuch as all of the transfer mechanisms 112 are the same, and operate the same, the description of the one shown in Figs. 17, 18 is applicable to them all, and no further detailed description of the individual mechanisms 112 is considered necessary. The wiring diagram of Fig. 19 shows the various transfer mechanisms 112 in relation to the particular work stations at which the respective work transfers take place, as also the ejector mechanisms 80, the locations 75 of which are shown in relation to the particular

work stations to which work automatically is ejected.

Briefly summarizing the operation of the disclosed apparatus, the work units or boxes W or W' are put on central conveyor belt 16 at station 1 of table 10 and deliver down track 74 to station 2 at which a worker places them on lower conveyor belt 14 for circulation in the circuitous pool operating between disks 56, 58. Each box W has a contact 102 thereon located for bridging the spring contacts 96, 98 at the approach to each of stations 3, 4, 5, 4a, 3a and 2a, while each box W' has a contact 102' thereon for bridging the spring contacts 96', 98' at the approach to each of the same stations. Boxes W and W' may contain different kinds of watches or parts, for example, and, if desired, the boxes W' at station 2, may be placed on center belt 16 to be delivered to stations further along table 10.

If the switch button 78 at any station between disks 56, 58 is free of a depressing box W or W', it will be closed so as to condition the ejector mechanism 80 at that station for operation as soon as a box contact 102 or 102' bridges the spring contacts 96, 98 or 96', 98', at the approach to that station. Hence, as soon as a box W or W' is removed by a worker from depressing relation to the switch button 78 at any of the stations 3, 4, 5, 4a, 3a or 2a, another box will be delivered to that station from the circuitous pool of work, regardless of conditions which may be prevailing at other stations along that pool.

After completing the assigned task on any work box W or W', each worker along the circuitous pool between disks 56, 58 places the box on the center belt 16 for delivery down a track 74 to station 6 at which the worker, after inspecting the box, places each back on the central belt 16 for delivery down a track 74 to station 7. At station 7, the worker places the boxes on lower conveyor belt 14 for circulation in the circuitous pool of work operating between disks 60, 62. Work boxes are ejected from this latter pool to the stations 8, 9, 10, 9a, 8a and 7a as soon as the switch button 78 at any of these stations closes in response to removal of a box from depressing relation to the button, as described in connection with the next previous pool.

The individual workers at stations 8, 9, 10, 9a, 8a and 7a, after completing work on boxes W or W', place the boxes on central belt 16 which carries them to the right along table 10 until the leading box is stopped against abutment 108. This leading box will be stopped opposite station 11a and closes spring contact 110 on the abutment 108 to condition the transfer mechanism 112 at station 11a for transferring the box which is against abutment 108 from the central belt 16 to the pivoted plate 192. However, the transfer mechanism 112 will not operate if a box W or W' on belt 18 is in position to engage and open any one of the series-connected switch contacts 188 at stations 12a and 11a. Hence, notwithstanding that abutment switch 110 may be held closed, mechanism 112 will transfer a work box from belt 16 to belt 18 at station 11a only if a suitable vacant space is open on belt 18 for reception of the transferred box. As a box is pushed laterally from belt 16 to the pivoted plate 192, the plate swings down to deposit the box on belt 18. Hence, it will be apparent that the circuitous pool of work operating between disks 64, 66 is automatically sup-

plied with work from central belt 16 as vacant spaces occur on the belt 18.

Stations 12, 13, 14, 13a and 12a are automatically supplied with work from the adjacent pool 5 by the associated ejector mechanisms 80, as described in connection with the preceding pools.

Work boxes placed on central belt 16 by the workers at stations 12, 13, 14, 13a and 12a are delivered to transverse belt 20 which delivers them to central belt 22 at table 12. The boxes are carried on central belt 22 to the left until the leading box is stopped against abutment 154, opposite station 15a. Spring contact 110 on abutment 154 is held closed by the leading box thereby conditioning the transfer mechanism 112 at station 15a for transfer of the leading box from belt 22 to belt 26 provided available space is open on the latter belt as determined by a closed condition of the series-connected spring contacts 188 at stations 16a and 15a. Hence the circuitous pool of work operating between disks 114, 116 automatically is supplied with work from central belt 22 in response to the occurrence of adequate vacant spaces on belt 26 for reception of transferred work boxes, and the stations 16, 17, 18, 19, 20, 19a, 18a, 17a and 16a automatically receive work from the adjacent pool in the same manner described in connection with the earlier described pools.

Automatic replenishing and maintenance of the supply of work in the other two circuitous pools along table 12, and automatic supplying of work to the work stations therealong, occurs in the same manner described in connection with the pool operating between disks 114, 116 and the stations along this pool, the work boxes ultimately arriving on central belt 22 at the left hand end of table 12, whence they may be removed and stacked on table 12 at station 31 or 31a, or they may be otherwise handled, as may be desired. For example, any conventional type of stacking device may be employed for removing the units W or W' from the central belt, at the end of the assembly line, and for stacking the removed units. Or the units may deliver to mechanism by which they may be removed on a level-changing principle, which may include a self-leveling platform.

It will be obvious that all of the circuitous pools of work may be supplied with work automatically by transfer mechanisms 112 so long as an adequate supply of work units is maintained on the central belt or belts from which transfer of work units may be effected, as needed, to the respective circuitous pools. Manual feeding of the first one or two pools, as herein disclosed, has been found convenient for ensuring an adequate supply of work in the initial pool or pools.

It will be apparent that specific details of the herein disclosed embodiment of the invention may be variously modified within the scope of the appended claims and it is intended that the patent shall cover the disclosed invention as broadly as is consistent with the terminology of the appended claims and the state of the pertinent prior art.

I claim as my invention:

1. A conveyor system for assembly lines and the like, comprising a support providing work stations arranged along the support, conveyor means adapted to circulate a plurality of pools of units of work past stations at different locations along the support, the units of work in one pool circulating past work stations in one

predetermined group of work stations, and the units of work in another pool circulating past work stations in another predetermined group of work stations, a straight-line conveyor for delivering units of work to a station past which one of said pools extends whereby a worker at that station is supplied with units of work for addition to the pool which is travelling past that station, ejector means at each of a plurality of said stations along each of said pools of circulating units of work for ejecting individual units of work from said pools to work-receiving positions at stations having said ejector means, and a switch button at each said work-receiving position responsive to removal of a unit of work from its work-receiving position thereby to condition a said ejector means for operation when a work unit in one of said pools is opposite that work-receiving position, said straight-line conveyor having extent for conveying units of work placed thereon at stations along one of said pools to the location of a next succeeding pool.

2. A conveyor system for assembly lines and the like, comprising a support providing work stations arranged along the support, means for circulating a pool of units of work past said work stations, a straight-line conveyor extending in relatively close general parallelism with the path of travel of units of work in said pool and adapted to convey units of work to said pool of circulating units of work, ejector means for transferring units of work from the straight-line conveyor into said pool, an abutment for stopping a unit of work on the straight-line conveyor opposite said ejector means, means responsive to a unit of work stopped against said abutment for conditioning the transfer means for transferring said stopped unit of work into said pool, and means responsive to work units on the circuitous conveyor for disabling the ejector means excepting when there is a vacant space on the circuitous conveyor into which a unit of work may be transferred.

3. A conveyor system for assembly lines and the like, comprising a support providing work stations arranged along opposite sides of the support, a pair of parallel conveyor belts travelling in opposite directions along said support at locations generally centrally between the opposite sides of the support, one of said belts travelling in one direction past the stations at one side of the support and the other of said belts travelling in the opposite direction past the stations at the opposite side of the support, a third conveyor belt located between and in a plane above said pair of belts and travelling in parallelism with the pair of belts in the same direction as one belt of the pair, a pair of rotatably mounted disks at substantially spaced apart locations along said support, said disks being located with their axes under said third conveyor belt and having radially extending disk portions overlying said pair of conveyor belts on opposite sides of said axes, there being means for effecting continuous rotation of said disks in the same direction when said belts are in motion, whereby said disks constitute means for carrying units of work from one to the other of said oppositely travelling belts of the pair thereby to cooperate with the pair of conveyor belts to circulate a pool of units of work past said work stations, means for ejecting a unit of work from said third conveyor belt to one of the belts of said pair thereby to maintain the supply of units of work in said pool, and means disposed in the path of units of work circulating

in said pool for disabling said ejecting means excepting when there is a vacant space in the pool for reception of a unit of work ejected from said third conveyor belt.

- 5 4. A conveyor system for assembly lines and the like, comprising a support providing work stations arranged along opposite sides of the support, a pair of parallel conveyor belts travelling in opposite directions along said support at locations generally centrally between the opposite sides of the support, one of said belts travelling in one direction past the stations at one side of the support and the other of said belts travelling in the opposite direction past the stations at the opposite side of the support, a third conveyor belt located between and in a plane above said pair of belts and travelling in parallelism with the pair of belts in the same direction as one belt of the pair, a pair of rotatably mounted disks at substantially spaced apart locations along said support, said disks being located with their axes under said third conveyor belt and having radially extending disk portions overlying said pair of conveyor belts on opposite sides of said axes, 20 there being means for effecting continuous rotation of said disks in the same direction when said belts are in motion, whereby said disks constitute means for carrying units of work from one to the other of said oppositely travelling belts of the pair thereby to cooperate with the pair of conveyor belts to circulate a pool of units of work past said work stations, means for pushing a unit of work from said third conveyor belt laterally toward one of said pair of belts, a pivoted member 25 normally bridging the path of travel of units of work in said pool and tilting in direction to deposit its unit of work on one belt of said pair thereby to add the said unit to said circulating pool of units, and means in the path of travel of units in said pool for disabling said pushing means when no vacant space is available 30 in said pool for reception of another unit of work.
- 35 5. A conveyor system for assembly lines and the like, comprising a support providing work stations arranged along the support, means providing a plurality of separate pools of circulating units of work at different locations along said support, each pool of units of work extending past different ones of said stations along the support, a straight-line conveyor extending past the said plurality of pools of circulating units of work and 40 in relatively close parallelism with a portion of the path of travel of units of work in each pool, said straight-line conveyor being adapted to convey units to the location of one of said pools and to convey units of work from stations along said 45 one pool to the location of the next succeeding pool, ejector means at one of said pools for transferring individual units of work from the straight-line conveyor into that pool, means in the path of travel of units in the latter said pool for conditioning the ejector means at that pool for a transferring operation only when a space is 50 vacant in that pool for reception of another unit of work, ejector means at each of a plurality of work stations along each pool for ejecting units of work from the adjacent pool to each of said plurality of stations along each pool, and means 55 at a work-receiving position of each of said plurality of stations along each pool for effecting an operation of the associated ejector means only 60
- 65
- 70
- 75

when the work-receiving position at any particular station is vacant.

6. A conveyor system for assembly lines and the like, comprising three parallel travelling conveyors of which two travel in opposite directions substantially in a common plane and the third conveyor is centrally disposed between the others and travels in a plane spaced above said common plane, means coating with said oppositely travelling conveyors which are in the said common plane for conducting work units from one of said conveyors to the other at one location therealong and for conducting work units from said other conveyor to said one conveyor at another location therealong, thereby to provide a circulating pool of work units between said conducting means, said centrally disposed conveyor being adapted to carry work units thereon for replenishing the supply of work units in said circulating pool of work units, means at spaced locations along said circulating pool of work units operative to eject a work unit from said pool at whichever one of said locations is in condition to receive a work unit, and transfer means operative only when there is a vacant space in said pool for transferring a work unit from said centrally disposed conveyor into said circulating pool of work units whenever a vacant space occurs in said pool due to ejection of a work unit therefrom at one of said locations spaced along the circulating pool of work units.

7. In a conveyor system for assembly lines and the like having a travelling conveyor on which

work units are carried, switch contacts at a predetermined location along the conveyor in position for at least one of them to be engaged by a work unit on the conveyor at said location, a normally closed switch at a receiving position adjacent to said location and to one side of said conveyor, said switch being adapted to be held open when a work unit occupies said receiving position, ejector means adjacent to said location and to the other side of said conveyor, said ejector means being operative for ejecting a work unit from the conveyor, and means providing an electric circuit, in which said switch contacts and switch are connected in series, for effecting an ejecting operation of said ejector means only when a work unit on the conveyor closes the circuit through said switch contacts while said normally closed switch is closed due to absence of a work unit in said receiving position.

ISADORE GALPER.
